SHUTTLE TRUING MACHINE

Francis O. Gibbs, Kernersville, N. C., assignor to
 Southern Silk Mills, Inc., Kernersville, N. C., a
 corporation of North Carolina

Application October 24, 1935, Serial No. 46,557

2 Claims. (Cl. 144—2)

This invention relates to a shuttle truing machine comprising means for holding the shuttle by its tips while a finishing operation is carried out on the shuttle, together with means for adjusting the position of the shuttle with relation to a rotary working tool. Means also are provided for adjusting the position of the working tool with relation to the shuttle. The combined apparatus provides means whereby the sides of a shuttle can be finished in such a manner that they are perfectly true thus resulting in better operation of the same when they are employed in looms for weaving.

It is, therefore, an object of the invention to provide means for holding a shuttle by its tips and subjecting the sides thereof to the action of a rotary cutting tool having points for engaging the side of the shuttle and cutting the same as the cutting tool is moved along the side of the shuttle, together with means for adjusting the position of the shuttle with relation to the cutting tool and also for adjusting the angularity of the cutting tool with relation to the shuttle.

It is a further object of the invention to provide means for holding a shuttle on a pivoted member and having means for adjusting the position of the pivoted member, together with the provision of a cutting tool for cutting away and finishing the sides of the shuttle.

Some of the objects of the invention having been stated, other objects will appear as the description proceeds when taken in connection with the accompanying drawings, in which:

Figure 1 is a plan view of the invention;

Figure 2 is an elevation of the upper front portion of Figure 1;

Figure 3 is a transverse sectional view taken along line 3—3 in Figure 1;

Figure 4 is a transverse sectional view taken along line 4—4 in Figure 1;

Figure 5 is a sectional view taken along line 5—5 in Figure 2;

Figure 6 is a sectional view taken along line 6—6 in Figure 2;

Figure 7 is a sectional plan view taken along line 7—7 in Figure 4;

Figure 8 is a vertical sectional view taken along line 8—8 in Figure 4;

Figure 9 is a sectional plan view of the central portion of Figure 1 and taken immediately below the motor;

Figure 10 is a vertical sectional view taken along line 10—10 in Figure 9;

Figure 11 is a plan view showing the ends of a shuttle being engaged by a pair of auxiliary

attachments which are adapted to be used when the extremities of the shuttle are slightly off center;

Figure 12 is an elevation of one of these auxiliary attachments secured to the standard shuttle 5

engaging means;

Figure 13 is a view looking along line 13—13 in

Figure 12.

Referring more specifically to the drawings, the numeral 10 denotes the base member of a 10 shuttle truing machine which has integral with the upper side and running longitudinally thereof of a tenon 11 which is adapted to be engaged by a mortise 12 of slide 13. Disposed between tenon 11 and mortise 12 is a shim 15 which is held in 15 position by means of set screws 15a to take up the lost motion between the tenon and mortise.

Mounted on the upper side of slide 13 is another member 14 by any suitable means such as stud bolts 16, which bolts penetrate slots 17 in 20 the member 14 and have their lower ends threadably secured in the upper side of slide 13. By providing the slots 17, the position of member 14 25 may be adjusted with relation to the slide 13. The member 14 has a downwardly extending lip 14a which is penetrated by set screws 18. The ends of these set screws contact the side of member 13 and assist the bolts 16 in holding the member 14 in its adjusted position. For example, if it is desired that the member 14 be adjusted at a 30 position so that its longitudinal axis will form a slight acute angle with the longitudinal axis of the base 10, the bolts 16 may be loosened and by manipulating the set screws 18 the member 14 35 may be adjusted in a slightly different position. The upper side of member 14 has a tenon 20 integral therewith over which is adapted to fit a mortise 21 of sliding support 22. A shim 19 is disposed between mortise 21 and tenon 20 in order to take up lost motion. The shim is held in position by means of set screws 19a. The support 22 has a vertical leg 24 integral therewith to 40 which is pivotally secured as at 25 a member 26, the pin 25 being secured in member 24 and loosely mounted in member 26.

By referring to Figures 4, 7 and 8, it is seen that stud bolts 29 and 30 penetrate slots 31 and 32 respectively in upstanding leg 24 and have the ends thereof threadably secured in member 26. This allows a limited adjustment of member 26 and its associated parts about the pivot point 25. Since the member 26 has an outstanding leg 26a projecting past the side of upstanding leg 24 with screws 33 and 34 threadably penetrating this leg and engaging the up- 55

standing leg 24, an adjustment can be easily made by loosening the stud bolts 29 and 30 and manipulating the screws 33 and 34 to re-position member 26 about pivot 25.

5 The member 26 has a tenon 36 integral therewith over which a mortise 37 of motor support 38 is adapted to slide. This support 38 has a circular band 39 integral therewith in which a suitable motor 40 is adapted to be placed and 10 held in clamped position by any suitable means such as screw 41. In order to take up the lost motion between tenon 36 and mortise 37 a shim 42 is provided which is held in position by means of set screws 42a.

15 Secured to motor shaft 43 is a chuck 44 in which the cutting tool 45 is adapted to be inserted. The tool 45 rotates at a very high speed and engages the sides of the shuttle 47 as shown in Figure 1. However, in order to properly cut 20 the sides from the shuttle to make it absolutely true, it is necessary to provide means for moving the cutting tool 45 longitudinally with the shuttle, transversely of the shuttle and in a vertical plane with respect to the shuttle.

25 In order to move the motor transversely of the shuttle to determine the thickness of the slice cut from the side thereof, a suitable threaded bore 50 is provided in member 14, said bore having mounted therein a threaded rod 51, (Fig. 10). This rod 51 penetrates downwardly 30 extending lip 14b and has a collar 53 disposed on one side of the lip, and fixedly secured to the rod 51 and a dial 54 is fixedly secured to rod 51 on the other side of the lip. On the end of rod 51 is a knurled nut 55 which is operated when it is desired to vary the movement of 35 slide 22, the cutting tool 45 and its associated parts transversely of the shuttle. A suitable pointer 57 is provided to allow one to accurately 40 gauge the amount which is being cut from the shuttle.

In order to move the cutting tool in a vertical plane a suitable threaded rod 60 is threadably secured in a bore 61 in member 26. The upper 45 end of rod 60 penetrates lip or flange 38a of member 38 and this rod has disposed on the lower side of the lip a collar 63 and on the upper side of said lip is fixedly secured on the end of the rod a knurled nut 64 which is operated when 50 it is desired to change the position of the motor and the cutting tool in a vertical plane.

In order to provide means for moving the cutting tool and its associated parts longitudinally of the shuttle a suitable threaded rod 65 is rotatably mounted in the end portions of tenon 55 11. The right-hand end of rod 65 has a collar 66 fixedly secured thereon and engaging one side of the end of tenon 11 and the end of rod 65 has fixedly secured thereon a hand wheel 67 60 which has a hub portion 68 engaging the other side of the end portion of tenon 11. The intermediate portion of rod 65 is supported by a collar 70, which collar is secured to the lower side of member 13.

65 By referring to Figures 4, 8 and 10, it is seen that a vertical bore 73 is located in the central portions of members 13 and 14 and has slidably mounted therein a pin 74, the lower end of said pin being hobbed to fit the threads on rod 65. The upper end of pin 74 has a transverse slot 70 therein in which is adapted to fit a projection 75 which is integral with pin 76, said pin 76 being rotatably mounted in member 14. On the end of pin 76 is a lever 77 which has pivotally secured 75 to the upper end thereof a link 78. This link is

used for operating the pins 74 and 76 and has the right-hand end thereof (Figs. 1 and 9), slidably mounted in a bracket 80 which in turn is secured to the top of member 14. Stop pin 79 extends outwardly to limit the rotative movement of lever 77. 5

In order to normally hold the pins 76 and 74 in the position shown in Figure 10, a tension spring 81 has been provided, said spring having one end thereof secured at the upper end of lever 77 and its other end secured to a suitable spring perch 82. Since the projection 75 is off-center with the main portion of the pin 76, it is evident that the rotation of pin 76 through the lever 77 and link 78 will cause pin 74 to rise 15 vertically. When this is done the lower end thereof will be disengaged from the threads on the rod 65. In this position the motor 40 and cutting tool 45 along with its associated parts may be moved longitudinally of the framework 20 10. In other words, the member 13 only has one means of engagement with rod 65 which is through the pin 74, and when this pin is disconnected from the rod the entire mounting may be moved longitudinally on the tenon 11. Of 25 course, this rotation of pin 76 is effected by pulling the link 78 to the right in Figures 1 and 9 and when the link 78 is released the spring 81, will automatically return the parts to normal 30 position as shown in Figure 10. 30

By referring to Figure 8 it is seen that projection 75 is disposed slightly to the left of the vertical center line of the main portion of pin 76 thereby causing any upward thrust exerted by pin 74 on projection 75 to hold the lever 77 35 against projection 79. 35

A set screw 83 is threadably secured in member 14 and has its lower end fitting in a suitable groove in pin 76 to prevent said pin from moving 40 out of its bore. 40

Base member 10 has pivotally mounted on the upper side thereof a shuttle supporting member 87 (Figs. 1 and 2). In order to provide a level surface on the upper side thereof, a plate 88 is secured on the upper side of member 87 by any 45 suitable means such as screws 89 and 90. These screws penetrate slots 84 and 85 respectively in member 87, which slots allow the position of plate 88 to be moved inwardly toward the motor so that the groove on the bottom side of the 50 shuttle will not be allowed to extend over the inner edge of the plate. Member 87 has a down-turned flange 87a on the inner side thereof which is engaged by set screws 91 and 92 to 55 properly position the pivoted member 87 on top of the base 10. This merely provides another means for adjusting the angularity of the shuttle with respect to the cutting tool since in some instances the shuttles vary in thickness slightly from one end to the other and it is necessary 60 to adjust the member 87 about its pivot point 86. Mounted in the upper left-hand portion of pivoted member 87, (Figs. 1 and 2), is a shuttle engaging means 93 which is comprised of an inclined portion 94 having a centrally disposed 65 groove 95 therein for the reception of the point of shuttle 47. The lower portion of member 93 has a tenon 96 which is adapted to fit in mortise 97 cut in the top of pivoted member 87. In order to fasten the member 93 in fixed position a suitable set screw 98 and a shim 99 are 70 provided for engaging the side of tenon 96 (Fig. 5). A similar member 100 is provided on the other end of the pivoted member 87 and is comprised of inclined member 101 having a cen- 75

trally disposed groove 102 cut therein for engaging the other point of the shuttle. This member has a tenon 103 on the lower portion thereof of which is adapted to fit in mortise 104 cut in the upper side of pivoted member 87.

Member 100 has a downwardly projecting lip 105 which is penetrated by a suitable threaded shaft 106, said bolt having a collar 107 disposed on one side of said lip and fixedly secured to shaft 106, and a knurled nut 108 is fixedly secured on the other side of lip 105 to the shaft 106. The threaded shaft 106 is threadably mounted in bore 110 in the right-hand end of pivoted member 87. By turning the knurled nut 108 it is evident that the member 100 may be moved longitudinally of the member 87 to cause the ends of the shuttle to be tightly secured between members 93 and 100.

In order to take up the play between tenon 103 and mortise 104 a shim 111 is provided which is held in position by means of set screw 109 (Fig. 6).

While the cutting tool 45 is shown for shearing the sides from the shuttle, it is to be understood that other tools can be substituted and the machine used for cutting the thread grooves, feeler slots and bottom grooves on the shuttles in the same precise manner that the tool 45 trues up the sides.

Figures 11 and 12 show an attachment which may be mounted on the member 93 when a right-hand or left-hand shuttle is being trued. One of the points of a shuttle of this type is off center and it is necessary that the shuttle be centrally located on the top of pivoted member 87 in order to be properly trued. This attachment will be designated by reference character 112. Disposed in collar 112 is a groove 113 which is slightly off center from the groove 95 in the member 93. The collar 112 is positioned on member 93 and a suitable set screw 114 is tightened to secure the member in place.

Figure 11 shows a top plan view of this member when it is attached to member 93 associated with shuttle 47a and shows how the groove 113 is off-set from the position of grooves 95 and 102 in order to re-position the shuttle 47a. It is necessary for the groove 113 in member 112 be off-set from the grooves 95 and 102 exactly the same amount as the tip of the shuttle 47a is off-set from its longitudinal center line, so

that when the attachment 112 is reversed to dotted line position as shown in Figure 13 and the shuttle is turned over, the edge thereof will project over the edge of plate 88 the same amount in each case.

In the drawings and specification there has been set forth a preferred embodiment of the invention, and although specific terms are employed, they are used in a generic and descriptive sense only, and not for purposes of limitation, the scope of the invention being set forth in the appended claims.

I claim:

1. In a shuttle truing machine having a pair of grooved members for engaging the ends of a shuttle and holding the same, one end of said shuttle being off-set from the longitudinal center line thereof, a motor driven rotary cutting member, means for moving the rotary cutting member while rotating alongside the shuttle, a grooved sleeve member insertable over one of the pair of grooved members and having an off-set groove therein for engaging the off-set end of said shuttle while a working operation is being performed on one side of the longitudinal center, said grooved sleeve member when removed and its ends reversed serving to hold the off-center shuttle for a working operation to be performed on its other side, and whereby each side of the shuttle will occupy approximately the same position with relation to the cutting tool.

2. In a shuttle truing machine, a base member, a trackway disposed longitudinally of the base member, a motor mounted for travel along said trackway and having a shaft disposed at approximately right angles to the trackway, a cutting tool mounted on said shaft, an upstanding portion disposed in parallel relation to the trackway, a table pivotally mounted intermediate its ends on said upstanding portion, a pair of converging members having their proximate faces grooved, means for fixedly securing the lower end of one of the converging members to said table, means for adjustably securing the lower end of the other converging member to said table, a collar insertable over one of the converging members and having an off-set groove in its face for reception of the tip of a shuttle having an end which is off-set from its center line.

FRANCIS O. GIBBS.
